(57) **CLAIM**

The ornamental design for a mandible guard, as shown and described.

DESCRIPTION

FIG. 1 is a top, front, right side perspective view of a mandible guard showing our new design; FIG. 2 is a front elevation view thereof; FIG. 3 is a rear elevation view thereof; FIG. 4 is a left side elevation view thereof; FIG. 5 is a right side elevation view thereof; FIG. 6 is a top plan view thereof; and, FIG. 7 is a bottom plan view thereof.

The broken lines illustrate portions of the mandible guard that form no part of the claimed design. The surface area between the left-side inner broken lines and the adjacent left-side slanted solid line quadrilateral in FIGS. 1, 2 and 4-7 forms no part of the claimed design. The surface area between the right-side inner broken lines and the adjacent right-side slanted solid line quadrilateral in FIGS. 1, 2 and 4-7 forms no part of the claimed design.
